UNITED STATES PATENT OFFICE.

ROBERT W. PAIN, OF NEW YORK, N. Y., ASSIGNOR TO THE AEOLIAN COMPANY, OF NEW YORK, N. Y., A CORPORATION OF CONNECTICUT.

TRACKER FOR MECHANICAL MUSICAL INSTRUMENTS.

SPECIFICATION forming part of Letters Patent No. 779,867, dated January 10, 1905.

Application filed October 13, 1903. Serial No. 176,891.

To all whom it may concern:

Be it known that I, ROBERT W. PAIN, a citizen of the United States, residing at New York city, in the county of New York and State of New York, have invented new and useful Improvements in Trackers for Mechanical Musical Instruments, of which the following is a specification.

This invention relates to improvements in tracker arrangements for mechanical musical instruments or musical-instrument players, and has for its object to provide a plurality of independently-usable trackers whereby, for example, music-sheets having perforations arranged on different scales to the transverse inch may be utilized in the same instrument. Music-sheets of the same width are, some of them, provided with note perforations on a scale of six to a transverse inch and others on a scale of eight to a transverse inch, requiring trackers having ducts arranged upon corresponding scales. By my invention provision is made whereby music-sheets with perforations arranged on different scales may be utilized in the same instrument.

My invention consists in the features herein-after described and then set forth in the clauses of the claim appended to the specification.

In the accompanying drawings, Figure 1 is a side elevation illustrating my invention. Fig. 2 is a detail showing a different arrangement of means for moving the trackers into and out of operative position. Fig. 3 is a front elevation, and Fig. 4 is a rear elevation, of the arrangement shown in Fig. 1.

In the said drawings, in which the preferred or best-known embodiment of my invention is illustrated, the reference-numeral 1 designates a part of the casing of the instrument, 2 and 3 music-sheet rolls, and 4 a sheet of music arranged thereon. These parts may be of the usual or any suitable construction and arrangement. Mounted in position to enable them to be brought into coöperative relation to said music-sheet are a plurality of trackers 5 6 of any known or suitable construction leading to related mechanism (well known, and therefore not herein illustrated or described) by means of tubes 7. Said trackers to ac-

complish the object for which my invention is 50 more particularly designed are provided with ducts of different range—that is say, they have to the inch a different number of ducts—and in the illustrated example of my invention are movably mounted on suitable guides 8, carried 55 by the casing or other support, which fit into grooves 9, provided therefor in the trackers. The trackers are moved into and out of coöperative relation with the music-sheet by means of a handle suitably pivoted in the casing and 60 having positive connection at opposite sides of the pivotal point with said trackers, whereby upon manipulation thereof the trackers will be moved simultaneously in opposite directions, the one into operative position and 65 the other out of such position. In Fig. 1 of the drawings the handle is designated by the reference-numeral 12, (shown pivoted at 12^a), to which handle a gear 11 is connected, and the tracker-boards are provided with racks 70 10, with which the gear meshes, thus affording a positive connection of the operating-handle at opposite sides of its center of movement with the tracker-board. In Fig. 2 of the drawings the handle is designated by the 75 reference-numeral 13 and the pivotal point thereof by the reference-numeral 13^a. This handle is provided at opposite points of its path or center of movement with elongated slots 14, taking over pins 14^a, connected to the tracker-boards, and its operation is the same as that referred to in connection with the mechanism shown in Fig. 1.

The numeral 15 designates a shield to close the ducts of that tracker which for the time 85 being is out of operation. In the drawings this shield is a pivoted one and is made up of a skeleton frame 16, inclosed in a suitable fabric 17, such as rubber-cloth or leather. The pivots 18 for the shield are shown as consisting of extensions of one part of the skeleton frame arranged in suitable sockets in the casing or other support. This shield may be manipulated in any suitable way—for example, by the operator shifting it with his hand 90 or by a handle 19, connected with its pivot. In the arrangement shown in the drawings by reason of the preferred but not essential

inclined position of the trackers said shield is in part automatic in its action—that is to say, when the uppermost of the plurality of trackers is projected into coöperative relation with 5 the music-sheet and the other thereof withdrawn from such relation the shield will automatically swing into position to close the ducts of the withdrawn tracker.

The plurality of trackers is particularly intended, as hereinbefore set forth, to enable music-sheets having note perforations arranged on different scales, as explained, to be utilized in the same instrument; but the invention is not restricted to such purpose or 15 use of the plurality of trackers, as other advantageous uses therefor may present themselves.

Having thus described my invention, what I claim is—

20 1. In an instrument of the character referred to, a plurality of movable trackers, and an operating-handle positively connected to said trackers at opposite sides of its pivotal

point whereby said trackers are simultaneously actuated, the one being brought into 25 operative position and the other moved out of operative position.

2. In an instrument of the character referred to, a plurality of movable trackers, provided with racks, and a gear meshing with 30 said racks.

3. In an instrument of the character referred to, a plurality of movable trackers provided with racks, a gear meshing with said racks whereby said trackers may be moved 35 into, and out of, operative position, and a shield for closing the ducts of said trackers when not in operative position.

In testimony whereof I have hereunto set my hand in presence of two subscribing witnesses.

ROBERT W. PAIN.
